ABSTRACT OF THE DISCLOSURE

A bath for treating textiles is provided by means of an apparatus having a container for the bath and separate supply containers for the bath components. The supply containers being connected with the bath by magnetic throttle valves and having level indicators provided with float valves.

This invention relates to an apparatus for producing treating baths for textiles and refers more particularly to an apparatus for producing treating baths which are made up of different components. The invention is especially concerned with an apparatus producing baths composed of different separate components which easily decompose when mixed, the mixing of such components taking place shortly before the bath is transmitted to the device applying it to the textiles.

By way of example, it is known that during the bleaching of textiles the alkali with the stabilizer and the peroxide which treat the textiles decompose within a short time, particularly in case of high concentrations, and thus lose a great deal of their effectiveness. However, foularding means with high concentrations are often used in many modern impregnating processes, such as so-called addition-impregnation. The quick decomposition and the small amounts used often make it necessary to add a new solution. This application of new solutions takes place as a charge in a container which is filled by hand with the separate components until the correct proportions have been provided. Immediately thereafter the solution is poured into a reserve container belonging to the impregnation unit and from there it is supplied in the required amounts by a dosing pump to the impregnating apparatus. In order to diminish the danger of decomposition during the storage periods the reserve container is usually made comparatively small, and this makes it necessary for the operators to often provide fresh solutions. It is apparent that the present procedure is inconvenient and time consuming and is liable to cause errors on the part of the operators.

An object of the present invention is to eliminate these prior art drawbacks.

Another object is to provide an extensive automation of bath production and to make readily available fresh baths of the desired consistency.

Other objects will become apparent in the course of the following specification.

In the accomplishment of the objectives of the present invention it was found desirable to provide several separate reserve containers for the individual components of the bath and to connect them with a reserve container for the ready bath by throttle valves, magnetic valves, discharging funnels or mixing funnels and conduits, whereby the magnetic valves are actuated by a float switch connected to the reserve container for the ready bath.

In accordance with one simplified embodiment of the present invention level containers with float valves can be provided between the supply containers and the

2

throttle valves in front of discharging funnels directed to the main reserve container; a swinging outflow conduit can be so arranged that a specific component of the mixture can be directed at will either into one of the funnels or into a measuring container, so that the ratio of the individual components of the solution can be always controlled.

According to a further improved embodiment of the present invention each reserve container for a specific component of the bath can be provided with a separate transmitting pump, preferably a displacement pump, whereby a bath component can be directed by a pump either back into the container through a volume measuring device, or into a mixing funnel. In order to avoid the possibility that the pump would be transmitting while the flow is closed, valves can be provided between the pressure conduits of the pumps and the mixing funnel. By means of these valves a certain amount of each liquid can be always returned into its container, so that no inadmissible rises in pressure can take place.

It is apparent that the production of baths from different components in accordance with the present invention is not limited to bleaching baths but can be also applied to all other chemical processes.

The invention will appear more clearly from the following detailed description when taken in connection with the accompanying drawings showing by way of example, preferred embodiments of the inventive idea.

In the drawings:

FIGURE 1 is a diagram illustrating a unit wherein the basic adjustment of the separate amounts of the components takes place prior to the operational use of the bath.

FIGURE 2 is a diagram illustrating an improved unit which makes it possible to control the amounts of the separate components during the operational use as well.

Similar parts designated by the same numerals throughout the drawings.

The drawings show by way of example devices used for producing a rewashing solution containing two components, namely, an alkali with a stabilizer and peroxide. When these components are separated, they can be preserved for any desired lengthy time periods. However, when they are mixed in the necessary proportions to form a treating solution a noticeable decomposition takes place after a short time even at room temperature. Consequently, only small amounts of the prepared solution are kept in the supply container 16 (FIGS. 1 and 2). The automatic preparation of the treating solution takes place in the following manner:

The apparatus shown in FIG. 1 has two supply containers 10. Each container 10 communicates with a funnel-shaped level container 18 containing a float valve 19 which always provides the same initial pressure in front of a throttle valve 11 connected with the container 18, the pressure being independent from the amount of liquid in the container 10. Each valve 11 is connected with a magnetic valve 12. The magnetic valves 12 are connected with a time contact switch 26 which can be set to a selected contact time.

In operation, one container 10 may be filled with NaOH while the other container 10 may be filled with peroxide. The liquids flow into the funnel-shaped level-indicating containers 18 having float valves 19. The throttle valves 11 and the magnetic valves 12 provide that depending upon the position of the throttle valves and the set contact time, predetermined amounts of liquids flow into the measuring containers 21 through the swingable outlets 20.

The throttle valve 11 for the peroxide is so set depending upon the desired mixing ratio of the two components

that during the time period set by the time contact switch the amount of the outflowing peroxide will be either a fraction or a multiple of the outflowing NaCH amount. The total amounts of the two components must jointly be always greater than the maximum amount transmitted by the dosing pump 27. After completion of the desired ratio and amount settings of the throttle valves the swingable outlets 20 are swung away from the measuring containers 21 and moved over the outlet funnels 13, the two magnetic valves 12 being switched to the float switch 17 in the container 16. Then the two component liquids leaving the containers 13 and flowing through the conduit 15 will be mixed in the container 16 for the pump 27 and their flow will continue until the container 16 is filled, whereupon the float valve 17 will simultaneously switch off the magnetic valves 12, thereby closing the valves 11 and interrupting the flow. The pump 27 will transmit the mixed liquid to the impregnating apparatus. This procedure can be repeated as long as it is necessary.

FIG. 2 shows a mixture preparing apparatus which is further improved in that it makes possible the control of the amounts of the separate components being mixed during operation as well. The apparatus includes the supply containers 10 for the two components. Pumps 22 transmit the two liquids the amounts of which have been determined by throttle valves 11', through measuring screens 23 and three-way magnetic valves 12' either into a mixing container 14 or back into the separate containers 10. The measuring devices 23 are connected with flow meters 24 which indicate the flowing amounts of the liquids and thus provide a control; when the flows are below a minimum amount or above a maximum amount they actuate optical and/or acoustic warning signals (not shown).

The mixed liquids flow from the container 14 into the container 16. When the supply container 16 is empty the float switch 17 supplies current to the magnetic valves 12' whereupon the two pumps 22 will supply predetermined amounts of the two liquids to the mixing container 14 from which the mixture will flow into the supply container 16. When the container 16 is full the float valve 17 is switched off and the magnetic valves 12' return to the initial position. The mixture is pumped into the impregnating apparatus in the usual manner.

It is apparent that the examples described above have been given solely by way of illustration and not by way of limitation and that they are capable of many variations and modifications within the scope of the present invention. All such variations and modifications are to be included within the scope of the present invention.

What is claimed is:

1. In an apparatus for producing a treating bath having a plurality of components, a separate supply container for each component, said supply containers having outlets, throttle valves, means connecting said throttle valves with said outlets, magnetic valve means connected with said throttle valves, a bath-receiving container, a float

valve in said bath-receiving container, means connecting said magnetic valve means with said float valve, and means connected with said magnetic valve means for supplying said components to said bath-receiving container, wherein the first-mentioned means comprise funnel-shaped level-indicating containers communicating with the outlets of said supply containers and having outlets communicating with said throttle valves, and a separate float valve in each funnel-shaped level-indicating container.

2. An apparatus in accordance with claim 1, wherein the last-mentioned means comprise a conduit leading to said bath-receiving container and a separate funnel for each component, said funnels communicating with said conduit, and outlet conduits connected with said magnetic valve means and leading to said funnels for transmitting said components to said funnels.

3. An apparatus in accordance with claim 2, further comprising a separate measuring container located close to each funnel, each of said outlet conduits being swingable between a measuring container and a funnel to transmit a bath component either to a funnel or to a measuring container.

4. An apparatus in accordance with claim 1, wherein the last-mentioned means comprise a mixing container, means supplying said components to said mixing container, and means supplying the mixed bath from said mixing container to said bath-receiving container.

5. An apparatus in accordance with claim 4, wherein the first-mentioned means comprise pumps communicating with the outlets of said supply containers and said throttle valves and wherein the means supplying said components to said mixing container include measuring devices and branch conduits transmitting said components either to said mixing container or back to their supply containers.

6. An apparatus for treating textiles with a bath having a plurality of components, said apparatus comprising at least two supply containers adapted to be filled with different liquid components and having outlets, two throttle valves, means connecting each throttle valve with the outlet of a separate container, a separate magnetic valve operatively connected with and actuating each throttle valve, a bath-receiving container, a float valve in said bath-receiving container, means operatively connecting said float valve with said magnetic valves, and means connected with said magnetic valves for supplying said components to said bath-receiving container.
